UNITED STATES PATENT OFFICE.

HENRY GEORGE PERCIVAL, OF LONDON, ENGLAND.

WHITE-LEAD CHAMBER.

SPECIFICATION forming part of Letters Patent No. 625,196, dated May 16, 1899.

Application filed June 13, 1898. Serial No. 683,838. (No model.)

To all whom it may concern:

Be it known that I, HENRY GEORGE PERCIVAL, a citizen of England, residing at Hythe House, Cumberland Park, London, England, have invented certain new and useful Improvements in White-Lead Chambers, (for which application for a patent has been made in Great Britain, No. 12,348, dated June 1, 1898,) of which the following is a specification.

10 This invention relates to the construction and arrangement of chambers for the manufacture of white lead in such a manner that the process can be managed externally without exposing workmen to the deleterious atmosphere within.

15 The particular process for which chambers according to this invention are intended is that of subjecting metallic lead to the action of acetic-acid vapor, air moisture, and carbonic anhydrid in suitable orders and quantities at suitable temperatures; but as this process is well known no claim is intended to be made in respect of it, but only to the construction and arrangement of the chambers 20 in which it is carried on, which will be described with reference to the accompanying drawings, in the several figures of which corresponding parts are denoted by like letters of reference.

25 Figures 1, 2, and 3 are sections on the lines 1 1, 2 2, and 3 3, respectively, of Figs. 4 and 5. Fig. 4 is a plan of the floor, partly broken away to show the air-spaces and heating-pipes below it. Fig. 5 is a plan at a lower 30 level, showing the air and gas conduits.

Under the floor are formed mixing-chambers *g*, which are supplied with air by a pipe *h* and with carbonic anhydrid by a pipe *f*, having two branches *f'*, opening near to the 35 walls of the channel, which act as deflectors, causing the gas to mingle with the air. The pipe *h* is supplied from an external shaft *c*, provided with a valve or damper *c'*. At the same low level there are other air-pipes *e*, which are supplied from external shafts *b*, and which bend upward and open into an air-chamber immediately under the floor. This chamber has in it rows of dwarf piers *p*, spanned by slabs *s*, which carry the floor, 40 consisting of slabs bedded on cement. Between the rows of piers are steam-pipes *a* for heating the floor and the air supplied by the

45 pipes *e*. The air-chamber containing the steam-pipes communicates with spaces *k* in the side and end walls, which are thus heated. Across the space *k* there are fixed several 50 short pipes *i*, which have openings to the exterior and interior of the chamber, and also lateral openings to the spaces in the walls. As any of these openings can be plugged from 55 outside, as shown at *z*, either cold or hot air or no air can be admitted by them to the chamber. The floor of the chamber is preferably made to slope a little from the sides and ends toward the middle, and through this 60 floor pass pipes *d*, which ascend from the mixing-chambers *g* below and extend some distance above the floor. Air-pipes *l* lead from the ceiling of the chamber to a space *o* in the roof, whence the air and gases pass to 65 a chimney *n*. Vapors are condensed in the exposed pipes *l* and the liquid collects in *o*, whence it returns to the chamber by a pipe *o'*. Each of the air-pipes *l* is provided with a 70 throttle-valve *Z* in any conveniently-accessible position. Windows *w* allow inspection 75 of the interior, and doors *m* serve to give access to the chamber, these doors being tightly closed while the process goes on. The interior of the chamber is fitted with framing *Q* 80 and shelves *S*, made of wood, to receive the trays containing the lead under treatment. The space between the adjacent curved portions of the two arches may be filled with concrete, as shown at *Y*. These being charged, 85 the doors are closed, the chamber is warmed, and the floor is covered with a layer of acetic acid, the vapors of which act on the lead. Afterward air and carbonic anhydrid are admitted in quantities suitably regulated by 90 valves or dampers, while the temperature is also regulated, as required, for the process, all the regulation being effected outside the chamber. When the process is completed, 95 the chamber is thoroughly ventilated, and then the doors can be opened to give access for removing the white lead produced and charging the chamber again.

Having thus described the nature of this invention and the best means I know for carrying the same into practical effect, I claim—

A chamber for the manufacture of white lead, having an air-space beneath the floor and air-spaces, communicating therewith, in

the walls, heating means for the air in said spaces, a mixing-chamber for air and carbonic anhydrid beneath the floor, communicating with the interior of the device, air-conduits leading through the walls of the chamber, communicating from the outside with the interior, and with the spaces in the walls, means for controlling the passage of air through said conduits, and valved discharge-pipes leading

from the interior of said chamber as and for the purpose set forth.

In testimony whereof I have hereunto set my hand in presence of two subscribing witnesses.

HENRY GEORGE PERCIVAL.
